UNITED STATES PATENT OFFICE.

BALTHASAR HEGELE, OF SAN JOSÉ, CALIFORNIA.

BOTTLE-STOPPERING DEVICE.

SPECIFICATION forming part of Letters Patent No. 237,015, dated January 25, 1881.

Application filed September 4, 1880. (No model.)

To all whom it may concern:

Be it known that I, BALTHASAR HEGELE, of San José, in the county of Santa Clara and State of California, have invented a new and valuable Improvement in Bottle-Stoppering Devices; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical central section of this invention. Fig. 2 represents a detail view of the stopper. Fig. 3 represents a detail bottom view of the three-spring plunger.

This invention has relation, mainly, to means for operating the stopper for my soda-water bottle for which a patent was granted to me on the 16th day of September, 1879; and it consists in providing the double stopper with a head having a square shoulder under it, joining it to the top of the upper cone; and it also consists in the construction and novel arrangement of the three-spring catch at the lower end of the plunger, and of the packing-box, in combination with the stem thereof, all as hereinafter shown and described.

In the accompanying drawings, the letter A designates a bottle constructed with a double-cone neck, such as is described in the Letters Patent above referred to.

B indicates the double stopper, which is designed to close the bottle when empty or when filled with soda-water or other carbonated liquid. This stopper is provided with a rubber flange, *a*, fitting in the groove *b*, and upon the top of the upper cone, *c*, of said stopper is formed a head, *d*, somewhat conoidal in form, and having an under shoulder, *e*. This head therefore forms a catch bearing entirely around the upper part of the upper cone.

C represents the plunger, and D the guide-stem, the latter being designed to work in bearings, being operated by means of a lever or other actuating device. The guide-stem is provided at its lower end with a stop-flange, *f*, and is centrally perforated and threaded in its lower end at *g* to receive the threaded end *h* of the plunger, which is thereby rendered de-

tachable. The lower end of the plunger C is provided with three spring-catches, *k*, extending downward and arranged equidistant from each other. The catch at the lower end of each spring is beveled in rounded form inward from the point, and is made in barb form, having a square shoulder, *l*. These spring-catches are provided with stems *s*, which are sufficiently stout and broad to preserve a certain amount of rigidity laterally, and have the inner walls, *m*, of each pair obliquely arranged with reference to each other, so that between each two catches there is an opening, *t*, having its walls shelving toward each other.

E indicates the packing-box, arranged on the plunger before it is screwed into the guide-stem. It consists of the sleeve F, having an exterior wrench-seat, *n*, an internally-threaded connection below for the stopper-chamber of the filling apparatus, and an internally-threaded connection above for the gland *r*.

When the stopper is put into the bottle-neck it seats itself upright on the lower conical bearing, and its head is in position to be grasped by the three-spring catch as the plunger descends. The operating lever is then raised, moving the plunger upward a short distance, and with it the stopper, until the latter is in the enlarged middle portion of the neck, when the bottle can be readily filled. The stopper is then raised to the upper bearing of the neck to close the bottle. After the operation the bottle is removed by drawing it sidewise, the upper cone passing out from its seat between the spring-catches by a wedging action against the oblique walls of the barbs.

By removing the plunger from the flanged stem the said stem will serve as an attachment for any ordinary bottling-table, and may be attached readily.

Having described this invention, what I claim, and desire to secure by Letters Patent, is—

1. In combination with a double conical bottle-stopper and its shouldered head *d*, the three-spring plunger C, having the barb-catches *k*, and above the same the packing-box E on the plunger-stem, substantially as specified.

2. The combination, with the centrally perforated and threaded guide-stem D, of the de-

tachable plunger *h* and its three-spring catch, substantially as specified.

3. In a bottle-stoppering machine, the combination, with the guide-stem *D* and the stopper-chamber, of the detachable plunger-stem *h*, the three-spring barb-catch, and the packing-box on said stem, having the under connection for the stopper-chamber, as specified.

In testimony that I claim the above I have hereunto subscribed my name in the presence of two witnesses.

BALTHASAR HEGELE.
